UNITED STATES PATENT OFFICE.

SIDNEY GEORGE BROWN, OF NORTH ACTON, LONDON, ENGLAND.

APPARATUS FOR TRANSMITTING OR REPRODUCING SOUND.

Application filed June 29, 1926, Serial No. 119,490, and in Great Britain September 19, 1925.

This invention relates to apparatus for transmitting or reproducing sound, more particularly telephone receivers.

In telephone receivers used for wireless 5 it is common to provide for adjustment of the air gap between the magnet pole pieces and the armature.

The object of the invention is to improve such means of adjustment.

10 The invention consists in the improved phonic apparatus hereinafter described and more particularly pointed out in the claims.

Referring to the accompanying drawings:—

15 Figure 1 shows an elevation with the cover and diaphragm removed of a telephone receiver ear-piece,

Figure 2 being a corresponding sectional elevation;

20 Figure 3 is a view looking on the back of Figure 1 with the casing removed, and

Figure 4 a perspective view showing the attachment of the pole pieces and bridge.

In carrying the invention into effect according to one form as applied by way of example to a telephone receiver ear-piece of the vibrating-reed type, the magnets are formed of two stampings, *a*, *b*, semi-circular in shape with the centre portion removed.

30 These are secured with their ends together by means of screws, *c*, *c*, to a brass back plate, *d*, which overlaps the two joints. The pole pieces, *e*, *e*, on which are mounted the usual coils, *f*, *f*, are secured to the magnets, *a*, *b*, at their joints by means of the screws, *c*, *c*. These two pole pieces butt towards one another at the centre leaving a small gap, *h*, (see Figure 4) between them. Over this gap is secured the reed, *i*, by means of

40 a screw, *k*, passing through one of said magnets, the reed in turn being attached to the diaphragm, *i*. The two pole pieces on the opposite side to the reed are secured by any suitable fastening means, *m*, *m*, to a bridge

45 or yoke-piece, *n*, of thin brass or other non-magnetic material which has its two ends bent into feet which are mounted by means of screws, *p*, *p*, on a solid piece of brass, *o*, or other non-magnetic material in the centre 50 of which is tapped a hole. A reed stop, *r*, may be provided upon this brass piece.

The magnets are secured to the casing, *s*, by means of two screws, *t*, *t*, situated one on each side of the reed and passed through 55 one of the magnets, *a*, the back plate, *d*, and the casing, *s*, and secured at the other end

by means of nuts, *u*, *u*. These screws are insulated from the magnets and the casing by means of bushes, thus acting as the terminals for leading in the current.

60

Through the back of the casing a set-screw, *v* is passed and screwed into the tapped hole in the brass piece, *o*, at the back of the bridge or yoke-piece, *n*, connecting the two pole pieces together. When this set-screw, *v*, is 65 turned, the pole pieces, *e*, *e*, of the magnets are drawn away from the vibrating reed and bend about their two ends secured to the magnets, the thin brass bridge or yoke-piece, *n*, being also slightly deformed.

70

It will thus be seen that the magnets are rigidly secured to the casing and that the pole pieces are secured to the magnet but at the same time are deformable by means of the milled nut at the back of the casing, thus 75 providing means for adjusting the air gap between the reed or armature and the pole pieces of the magnet, while maintaining rigidity of support for the pole pieces.

The invention is applicable to any type of 80 apparatus for transmitting or reproducing sound in which a vibrating element is employed.

Having now described my invention what I claim as new and desire to secure by Letters Patent is:—

85

1. In phonic apparatus the combination comprising an electro-magnet having pole pieces with an air gap therebetween, a flexible non-magnetic yoke piece mounted upon 90 and bridging the gap between said pole pieces, a rigid member supporting said yoke piece, an armature situated over said air gap and means attached to said rigid member for bending said yoke piece together 95 with said pole pieces towards and away from said armature, as set forth.

2. In phonic apparatus the combination comprising magnets having pole pieces with an air gap therebetween, a flexible non-magnetic yoke piece mounted upon and bridging the gap between said pole pieces, windings 100 surrounding said pole pieces and portions of said yoke piece, lugs projecting from said yoke piece, a non-magnetic rigid member attached to said lugs, and means attached to said rigid member for bending said yoke piece together with said pole pieces relative to said magnet, as set forth.

105

3. Phonic apparatus as claimed in claim 1, in which the rigid member is provided with an adjustable stop to prevent the 110

115

armature from making contact with the pole pieces, as set forth.

4. Phonic apparatus as claimed in claim 2, in which the rigid member is in the form of a strip and is arranged transversely of the pole pieces.

5. A telephone receiver comprising in combination, an electro-magnet having pole pieces with an air gap therebetween, a reed 10 adapted to vibrate mounted over said air gap, a diaphragm attached to said reed, a

flexible non-magnetic yoke piece mounted upon said pole pieces and bridging the air gap on the opposite side to said reed, a rigid member attached to said yoke piece, and means attached to said rigid member for bending said yoke piece together with said pole pieces towards and away from said reed. 15

In testimony whereof I have signed my name to this specification.

SIDNEY GEORGE BROWN.
